Delaware

Application January 22, 1943, Serial No. 473,264

3 Claims. (Cl. 33—225)

1

This invention relates to deviation correcting means for magnetic devices responsive to the horizontal component of the earth's magnetic field.

One of the objects of the invention is to compensate or correct against errors in a magnetic compass instrument due to presence in the vicinity of the compass of both fixed and temporary sources of local magnetic attraction or disturbance.

A further object of the invention is to facilitate ready adjustment of the deviation correcting means for a magnetic compass of the type which may or may not be located at a remote position on the dirigible craft in which it is employed.

One of the features of the invention resides in the provision of coil means situated in the vicinity of the sensitive element of the magnetic device from which a controllable resultant corrective flux field may be obtained.

Another feature of the invention consists in provision of circuit means for controlling the respective deviation correcting coils for the fixed source of local effects and each of the individual temporary and transient sources of such effects.

A still further feature resides in the provision for making the circuit means correcting the compass for deviation due to a temporary local deviation causing attraction automatically effective.

Other objects, features and structural details of the invention will be apparent from the following description when read in relation to the accompanying drawings, wherein

Fig. 1 is a perspective view of a dirigible craft such as an airplane showing a magnetic compass system in which the present invention is incorporated.

Fig. 2 is a detail view, partly in vertical cross section showing one of the magnetic devices in which the present inventive concepts may be included.

Fig. 3 is a side elevation, with the casing in vertical section, showing the invention adapted for use in a repeater compass controlling type of magnetic compass.

Figs. 4 and 5 are circuit diagrams illustrating the electrical connections for the elements constituting one form of the improved magnetic compass correcting means.

Fig. 6 is a view similar to Fig. 3 showing the invention adapted for use with the sensitive element of a flux valve type of magnetic compass, and

2

Fig. 7 is a further circuit diagram showing a practical adaptation of the invention in a craft of the character noted in Fig. 1 in which the controls for the respective deviation effects are situated in a single corrector panel.

In the form of the invention shown in Fig. 2, the magnetic compass instrument is of the direct reading type that may be located on the instrument board panel 10 of a dirigible craft or airplane 11, Fig. 1. This instrument is generally similar in character to the type of magnetic compass shown and described in U. S. Letters Patent No. 2,300,404, issued November 3, 1942, to L. F. Carter and W. Ainscott, with the remote reading features of the therein disclosed instrument eliminated. This instrument as shown in Fig. 2 includes a casing 12 in the front of which is a window 13 through which a side reading compass card 14 is visible to an observer. Card 14 is read in connection with a suitable vertical extending rubber line provided in the present construction by the forward portion of a bent rod 15. The sensitive element of the magnetic compass is provided by two spaced permanent magnets, one of which is indicated at 16, the same being responsive to the horizontal component of the earth's magnetic field. The magnets are spaced in parallel relation by means of suitable mounting pieces 17 contained in the body of the compass card providing casing 18. Card casing 18 is mounted for pivotal movement about a vertical axis by means of shaft 19 which is supported in suitable upper and lower jewel posts in a vertical frame 20. The rearward ends of the rod 15 are fixed to the frame 20. It will be understood that the magnets 16, card housing 18 with the side reading compass card thereon and the shaft 19 move as a unit with respect to the frame 20.

Frame 20 and consequently the sensitive element of the magnetic compass may be stabilized by means of a suitable gyro vertical instrument as generally indicated at 22. In the manner shown more in detail in the hereinbefore mentioned patent, the frame 20 is universally mounted by means of a bifurcated member 23 that extends from and is fixed to the gimbal ring of the gyro vertical. The extending arms of the member 23 have inwardly disposed trunnions, one of which is noted at 24 that journal in suitable bearings 25 in the oppositely disposed legs of the frame 20. Tilt of the frame 20 about the thus defined athwartship axis of horizontal support of the frame with reference to the craft is controlled by link 26. Similarly

the fore and aft horizontal axis of universal support of the frame 20 is provided by the bifurcated extension member 23 of the gimbal ring of the gyro vertical instrument. The rotor bearing case and gimbal ring of the gyro vertical instrument are respectively indicated at 27 and 28. The gyro instrument is of conventional form and is employed herein to maintain the sensitive element of the illustrated magnetic compass in a horizontal plane with reference to the earth's surface.

The deviation correcting means shown in Fig. 2 consists of a plurality of coils that are mounted within the casing or compass housing 12 with the axes thereof arranged in fixed mutually perpendicular relation. In the form of the invention shown, coils of the "Helmholtz" type are employed. The coil arranged in coaxial relation with the fore and aft axis of universal support of compass frame 20 is indicated at 30. The coil at right angles to the same is provided by two spaced parallel coils 31, only one of which is shown. Coils 31 are coaxial, in this instance, with the athwartship axis of universal mounting of the compass frame 20. As shown, the coils may be connected to the inner wall of the casing or housing 12.

The coils of the correcting means are positioned adjacent the magnetic device or compass, and the respective axes thereof are arranged in spaced angular relation to one another in a horizontal plane, such relationship preferably being as shown in the drawing.

In the form of the invention shown in Fig. 3, the magnetic compass is adapted for connection with a repeater compass which it controls, the sensitive element of the combination being located at a remote position on craft 11 such as at the end of the wing of the same. The housing or casing of this instrument is indicated at 33 in Figs. 1 and 3. There may be one or a plurality of repeater compasses, one of the same being indicated at 34 on the instrument board panel 10 of the craft. A cable connection 35 is shown linking the controller and controlled instrument which are described in detail in regard to the remote control features of the aforementioned application. With reference to Fig. 3, the sensitive element of the magnetic compass shown therein comprises a bar magnet 36 which is mounted on the upwardly extending shaft 37 of the rotor of a "selsyn" type transmitter whose casing is indicated at 38. The transmitter and bar 36 are pendulously supported within the housing 33 by means of the gimbal ring 39 which also mounts the same for universal movement, the arrangement normally maintaining bar 36 in horizontal position. The compensating or correcting means provided in this instance include spaced pairs of coils 30' of the "Helmholtz" type that are arranged substantially coaxial with the bar, as viewed in Fig. 3, about its fore and aft axis of universal support. Paired coils 31', only one of which is shown, are similar to coils 31 previously described. In this form of the invention a further pair of coils 41 may be employed, the same being coaxial with shaft 37, as viewed in Fig. 3, and being also mounted within the housing or casing 33 in a fixed location on the inner wall of the housing.

The circuit shown in Fig. 4 may be employed in the forms of the invention illustrated in both Figs. 2 and 3. As shown, a current source is generally indicated at 42 which may be a battery,

the same providing a means for supplying the respective coils with energy from a common source. To control the polarity of the coils, a common lead 43 is connected to a center tap position on the battery 42. Coil 30 or paired, series-connected coils 30' may be energized from the source by way of lead 44 and potentiometer 47. Similarly, supply leads 45 and 46 are respectively provided for the series-connected coils 31 or 31' and for coils 41. The energy supplied these respective coils is controlled by potentiometers 48 and 49. The polarity and current in the reversible circuits thus provided may be ascertained by employing a suitable ammeter in the respective leads 44, 45 and 46. Such ammeters are respectively indicated at 15, 16 and 17. By adjusting the position of the variable arm of the potentiometers to either side of a balanced central position, the energy supplied to the individual coils is controlled in such a manner as to obtain a resultant flux field from the combined coils that is effective to correct the sensitive element of the magnetic compass in this instance against any deviation thereof due to fixed deviation causing effects. In accordance with the terminology employed herein, local fixed deviation causing effects in the craft or airplane may be considered to be a resultant deflecting magnetic field due to the combined effect of all of the magnetic field radiating or attracting bodies fixedly incorporated in the structure of the craft. The same or a similar separate circuit may be employed for correcting a magnetic device of this character against deviation due to temporary sources of attraction such as may be considered to be caused by releasable objects on the craft such as bombs or torpedoes. The potentiometers 47, 48, 49 provide a means for regulating the fields of the individual coils employed to obtain a resultant corrective flux field compensating the sensitive element of the magnetic compass against deviation thereof due to the resultant of such local and/or transient fixed deviation causing effects. In the form of the invention shown in Fig. 3, the coil means in the vicinity of the magnetic compass is located in the remotely positioned compass housing. The adjusting potentiometers may be located on the instrument board panel 10, or in any other convenient location, thus facilitating the correction of the repeater compass through the magnetic compass instrument 33 without the necessity of a physical adjustment of an individual error compensator at the remote position. The ability to control a magnetic correcting device from a remote position is one of the primary advantages of the present invention. In the normal operation of a given craft, the potentiometers 47, 48 or 41, 48 and 49 may be adjusted as required upon change of the temporary source of local attraction if the circuit is utilized in this connection. The invention also contemplates the utilization of the improved deviation correcting means for also correcting the magnetic compass for transient deviation causing local effects such as resulting from a radio transmitter or receiver, special electrical equipment, or other conditions of a transiently effective nature. A separate controlling circuit for the correcting means for each piece of electrical equipment of this character may be provided as particularly shown in Fig. 7. In Fig. 5, a single specific piece of electrical equipment such as a radio trans-

mitter 80 is employed for illustrative purposes in this connection.

The magnetic device responsive to the horizontal component of the earth's magnetic field employed in connection with the form of the invention shown in Fig. 6 is an earth inductor compass of the flux valve type such as specifically shown and described in the copending application of Orland E. Esval, Robert S. Curry, Caesar F. Fragola and Lennox F. Beach, Serial No. 414,422 filed October 10, 1941, for Flux valve compass system, which became Patent No. 2,383,461, issued August 28, 1945. The sensitive element of the flux valve generally designated at 52 is pendulously supported within a housing 33' on a universal mounting provided by the gimbal ring 54, the output coils of the valve being situated in a horizontal plane with reference to the earth. Housing 33' is positioned as shown in Fig. 1 at a remote location from the repeater compass 34 which is controlled thereby, it being understood that the output of the valve is fed by way of cable 35 to the repeater compass. The exciting and output coils of the flux valve are respectively indicated at 55 and 56. The correcting coil means employed in this form of the invention consists of two perpendicularly crossed electromagnets that may be fixedly mounted in a protective enclosure at the base of the housing 33'. The cores and coils of these individual electromagnets are respectively indicated, in Figs. 5 and 6, at 57, 58 and 59, 60. A controllable circuit means similar to that previously described is provided for regulating the flow of energy to the coils 59 and 60, Fig. 5, to correct the output of the flux valve for change thereof due to local fixed and temporary deviation causing effects. As shown in Fig. 5, a second or auxiliary circuit means is provided to correct the output of the valve for deviation thereof due to operation of the radio transmitter 50 or other transient local deviation causing attraction which itself may be energized when a switch 68 in series with the battery 62 is closed. The second circuit means includes, in this instance, the common lead 43, with the further leads 63 and 64 and potentiometers 65 and 66, respectively. It will be understood that the resultant field set up by the electromagnets influences the sensitive element of the flux valve so that the output thereof is changed or corrected. A number of separate circuits, similar to the described second circuit, for each of the transient sources of deviation causing disturbances in the craft may be employed as herein-after more particularly described. The compass or magnetic device is thus compensated for the described type of disturbances through the single correcting means. Once adjustment of the potentiometers 65 and 66 for a particular or number of particular disturbing transient causes of deviation of the magnetic compass has been made, no further regulation may be needed and the circuits are automatically effective to obtain the needed correction from the compensating means upon closure of the switch to the particular or number of particular deviation causing electrical instruments.

It will be understood that the correcting means may also be utilized in connection with a compass of the rotary earth inductor type. Also, the compensating coils, if desired, may be constructed for direct mounting on the pendulous portion of the compass instrument shown in Figs. 3 and 6 or on the stabilized frame 20 of the instrument shown in Fig. 2 with equal effectiveness.

A circuit arrangement is shown in Fig. 7 by which a single correcting means 80 of the type shown in Fig. 6 may be controlled from a corrector panel 81 situated at the instrument board panel of the craft. In this instance, three sources of transient deviation causing effects are illustrated, the same being radio transmitter 50, radio receiver 82 and electric pilot 83. The control panel 81 includes ammeters 84 and 85 and a number of paired potentiometers with common lead 86. The pair of potentiometers 87 and 88 are employed to correct the compass against deviation due to fixed deviation effects. Once the setting of these potentiometers is made the same will remain fixed. Superimposed on the fixed correcting signal are further signals resulting from five other circuits in this instance, two of which compensate the compass for errors due to temporary deviation causing effects. These last circuits are controlled by the respective paired potentiometers 89-90 and 91-92. If for example, a separate deviation correcting circuit is provided for each of the temporary causes of deviation, when a change occurs and the cause of deviation is no longer present, the proper circuit is restored to a balanced condition by adjustment of the potentiometers. This alters the supply of current to the coil or correcting means to recorrect the compass for the resulting change in the fixed and temporary deviation causing effects.

The other individual currents provide additional control whereby the supply of energy to the individual coils is regulated to correct the device against deviation due to transient local deviation causing effects. Paired potentiometers 93-94 control the flow of current to the coils when the electric pilot 83 is rendered effective by closure of the switch 95. A further similar control circuit is provided for the radio receiver 82 which includes switch 96 and the paired potentiometers 99-100. Potentiometers 97-98 are provided for the control circuit rendered effective by closure of the switch 68 for the radio transmitter 50.

The operation of the circuit illustrated in Fig. 7 should be understood from the following brief description thereof. It will be noted that the battery 101 is connected, under normal operating conditions, across the potentiometers 87 through 82 and therefore that the setting of these potentiometers continuously controls the magnitude and direction of the resultant field produced by the magnetic device 80. The voltages derived from these potentiometers control the magnetic device to correct for fixed or continuously existing deviation effects. Assuming, however, that the switch 96 is closed, placing the radio receiver 82 in operation, the battery will then be connected across the potentiometers 99 and 100 thereby impressing a voltage across both potentiometers. This circuit may be traced from one side of the battery 101 through conductor 102, switch 96, and conductor 103 to the common connection 104 between potentiometers 99 and 100. The other ends of these potentiometers are both connected to conductor 105 which, in turn, is connected to the other side of battery 101. The wipers of these potentiometers are adjusted to pick off a voltage therefrom of the correct magnitude and polarity sense, when applied to the magnetic device 80, as to vary the magnitude or the direction, or both, of the field produced by the magnetic device, and this change will necessarily be of a fixed, predetermined value only,

whereby to correct for the deviation error otherwise caused by the radio receiver on the magnetic compass. The wiper of potentiometer 99 is connected to conductor 106 which through ammeter 84 is connected with one coil of the magnetic device 80, and the wiper of potentiometer 100 is connected through conductor 107 in a similar manner to another coil of the magnetic device. The common return lead 86 from the magnetic device is connected with jumper 108 which is connected between preferably the mid-points of the two potentiometers 99 and 100. It should be evident from the foregoing that the circuit of Fig. 7, so far as it relates to one of the devices providing temporary deviation effects, is quite similar to the circuit illustrated in Fig. 5. Adjustment of the wipers of these potentiometers will determine the polarity sense of the voltages applied to the coils embodied in the magnetic device, and also the magnitudes thereof. Further, it will be observed that the switch 86 functions as a common means for connecting and disconnecting the battery with the potentiometers 99 and 100 with on-off control of the temporary deviation-causing apparatus. By operating the various switches 68, 96 and 95, the respective potentiometers associated therewith will be rendered operative and inoperative to control the magnetic field developed by the magnetic device 80.

It is to be understood that the term "magnetic compass" as employed in the appended claims is intended to include all devices which are sensitive to an external magnetic field such, for example, as compasses comprising field-sensitive magnetic needles or those of the flux valve type which provide a signal voltage output as an indication of the direction of an external field relative thereto.

Since many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. In a system for correcting for deviation effects of a magnetic compass, the combination with an intermittently operable deviation-causing apparatus and a magnetic compass mounted in subjective relation thereto, of a plurality of relatively angularly disposed coils mounted in cooperable relation to said compass, means for providing a continuous and controlled energization of said coils to thereby provide a magnetic field of a first predetermined intensity and direction to compensate the compass for local fixed deviation-causing effects, means for additionally controlling the current flow respectively in all of said coils to subject said compass to a field of a second fixed and predetermined value in magnitude and direction substantially equal and opposite to the combined magnetic effect of said apparatus and the local fixed deviation-causing effects on said compass, and a switch for rendering said last mentioned means operative and inoperative in timed relation to an "on-off" control of said apparatus.

2. In a system for correcting for deviation effects of a magnetic compass, the combination

with an intermittently operable deviation-causing apparatus and a magnetic compass mounted in subjective relation thereto, of means comprising three coils having their axes arranged in mutually perpendicular relationship and in cooperable relation to said compass, means for providing a continuous and controlled energization of said coils to thereby provide a magnetic field of a first predetermined intensity and direction to compensate the compass for local fixed deviation-causing effects, means for additionally controlling the current flow respectively in all of said coils to subject said compass to a field of a second fixed and predetermined value in magnitude and direction substantially equal and opposite to the combined magnetic effect of said apparatus and the local fixed deviation-causing effects on said compass, and a switch for rendering said last mentioned means operative and inoperative in timed relation to an "on-off" control of said apparatus.

3. In a system for correcting for deviation effects of a magnetic compass, the combination with an intermittently operable deviation-causing apparatus and a magnetic compass mounted in subjective relation thereto, of a plurality of relatively angularly disposed coils mounted in cooperable relation to said compass, means for providing a continuous and controlled energization of said coils to thereby provide a magnetic field of a first predetermined intensity and direction to compensate the compass for local fixed deviation-causing effects, means for additionally controlling the current flow respectively in all of said coils to subject said compass to a field of a second fixed and predetermined value in magnitude and direction substantially equal and opposite to the combined magnetic effect of said apparatus and the local fixed deviation-causing effects on said compass, and a common means for controlling the operation of said apparatus and the operation of said means for additionally controlling the current flow respectively in all of the coils whereby simultaneously to change the value of the magnetic field developed by said coils from one value to another when said apparatus is turned on and off.
